UNITED STATES PATENT OFFICE.

JOSEPH H. JACKSON, OF HAMILTON, ONTARIO, CANADA.

TYPE-WRITING MACHINE.

No. 867,045.

Specification of Letters Patent.

Patented Sept. 24, 1907.

Application filed March 2, 1906. Serial No. 303,786.

To all whom it may concern:

Be it known that I, JOSEPH H. JACKSON, a citizen of the United States, and a resident of Hamilton, in the county of Wentworth and Province of Ontario, Canada, 5 have invented new and useful Improvements in Type-Writing Machines, of which the following is a specification.

This invention relates to typewriting machines, and has for its object to improve the construction and decrease the noise caused by impact of the keys upon the 10 roller, as well as to increase the strength, durability, utility and efficiency of devices of this character.

With these and other objects in view the invention comprises as one feature of the same a cylinder or drum 15 having spaced longitudinal peripheral ribs whereby a plurality of corresponding recesses or spaces are formed upon the surface of the drum, and a resilient belt extending over the ribs of said drum and the spaces between the same.

20 The invention further consists in a cylinder or drum having spaced longitudinal peripheral ribs whereby a plurality of corresponding longitudinal recesses are formed between the ribs, an idler roller spaced from the cylinder or drum, and a resilient endless belt 25 extending from the cylinder and drum.

The invention further consists in a cylinder or drum having flanges at the ends and with spaced longitudinal peripheral ribs extending between the flanges, and a resilient belt extending over the ribs and the spaces 30 between the same, the flanges having lateral vent apertures communicating with the recesses between the ribs.

The invention further consists in various combinations and arrangements of parts as hereafter described 35 and specifically pointed out in the claims. In the drawings forming a part of this application, and in which corresponding parts are denoted by the same designating characters.

Figure 1, is an end elevation of the device, showing 40 one end of the carriage, with the end flanges of the ribbed cylinder and roller removed, in order to show the cylinder, the roller, and the endless belt tensioning device. Fig. 2, is a plan view of the same with both ends of the carriage in position but with the endless belt, the printing paper, and the printing table removed. Fig. 3, is an end elevation of one of the end flanges for guiding the belt on the corrugated cylinder, 45 showing air perforations through the same. Fig. 4, is a transverse section enlarged of the ribbed cylinder and with the endless belt also in section over the same. Fig. 5, is a transverse section enlarged of the ribbed cylinder showing a modified construction of the same. Fig. 6, is a transverse section enlarged of the ribbed cylinder constructed as in Fig. 5, and with the endless 50 belt thereon.

Similar letters refer to similar parts throughout the several views.

In the drawing, the movable carriage of a type-writing machine is indicated by A, and the ribbed cylindrical roller by B, which is suitably mounted in 60 the carriage and adapted to revolve therein. The cylinder B, is mounted on a shaft 2, which extends beyond the carriage A, and said carriage has suitable slots 3, which extend a certain distance to receive the extended ends of the shaft and thus support the 65 same. The cylinder shows eight horizontal ribs which extend from end to end of the same, but a greater or lesser number of ribs may be employed if deemed expedient. The cylinder B, has end flanges 4, to guide the belt, and which have a number of perforations 70 5, to correspond with the spaces formed by said ribs, in the periphery of the cylinder. Other forms of perforations, or openings 5, may be employed for the admission of air to the spaces between the lines.

On the inner sides of the carriage A, are adjustable 7 extension arms, or brackets C, and D. The arms C, are journaled on the shaft 2, of the cylinder, and the opposite and outer ends of the arms D, are adjustably secured to the carriage A, by means of screws 6, which extend through the carriage A, and through slotted 8 holes 7, in the arms D, and into the nuts 8, on the sides of the arms D. At the central connection of the arms C, and D, the arms D, have upper and lower flanges 9, and the end of the arms C, fit between said flanges 9, and are adapted to slide therein. The screws E, extend through slotted holes 12, in the arms D, and through the arms C, and into nuts 13, to allow the adjustment of the arms, and to secure the same rigidly together. When the screws E, are firmly set, then the screws 6, are also firmly set, to hold the arms C, and D, rigid with the carriage A.

F, is a roller parallel with the cylinder B and provided with end journals V, and 14 are slots in the arms D, for the journals V, to revolve in.

The arms C, C are connected by tie members C', and the arms D are connected by a tie member D'.

The cylinder B, and the roller F, are connected by an endless belt H, and the arms C, and D, are adapted to tension the said belt, by means previously referred to.

J, is the writing paper, which fits closely to the belt H, and is carried by said belt. The right-hand or rear side of the carriage show the two ends of the writing paper.

K, is the writing paper table, which is supported by the arms D, by pivotal connection 15, to the lower extension 16, of said arms D. The forward part of the table K, is connected to the arms C, by means of spiral springs 8; the lower ends of the springs are secured to the table K, and the upper ends of the springs are connected to adjustable screw shanks M, on the arms C.

and which are adjusted by the hand wheels N, on said screws. The wheels N, by manipulation are adapted to raise and lower the screw shanks M, consequently the springs S, receive more or less tension in order to engage the paper table K, more or less, with the paper J.

P, is a roller suitably journaled in brackets R, which are secured to the forward part of the table K, and when the wheel N, referred to, is manipulated, the roller P, is brought into contact, or more or less tension, with the paper J, and previous to writing on the paper, to retain the paper in proper position on the belt H, to facilitate writing on the paper.

The type-carrying arms of the type-writing machine 15 may impress on the paper J, and opposite to the spaces between the ribs of the cylinder B, in any convenient place on the cylinder according to the adjustment of the type carrying arms, and the set, or adjustment of the type on the arms.

20 It will be obvious that when the type arms engage the paper on the cylinder and opposite to a space between the ribs, of the cylinder, that a pneumatic cushion is formed for said engagement of the type on the paper. More or less cushion is formed by the thickness of the belt, together with the composition of the material of the belt.

In Fig. 5, of the drawing is shown a covering T, around the ribbed cylinder B, the cylinder with its covering T, is introduced into type-writing machines 30 without an endless belt, to form pneumatic cushions for the type carrying arms. Also the covering T, is applied to the ribbed cylinder, between the endless belt and the cylinder, if deemed desirable.

The cover T, preserves the circular line of the ribbed 35 cylinder.

What I claim as my invention and desire to secure by Letters Patent, is:—

1. In a typewriter, end frames spaced apart and having 40 bearings at their ends, shafts journaled in said bearings, a roller carried by one of said shafts, a roller carried by the other of said shafts and provided with spaced longitudinally extending peripheral ribs and with flanges at the ends bearing against the ends of said ribs, said flanges having transverse apertures communicating with the spaces

between the ribs, and an endless belt of resilient material 45 bearing over said rollers.

2. In typewriter, end frames spaced apart and having bearings at their ends, shafts journaled in said bearings, a roller carried by one of said shafts, a roller carried by the other of said shafts and provided with spaced longitudinally extending peripheral ribs and with flanges at the ends bearing against the ends of said ribs, said flanges having transverse apertures communicating with the spaces between the ribs, an endless belt of resilient material bearing over said rollers, bars swinging from the journals of said rollers and over-lapping at their inner ends, and means for adjustably connecting said over-lapping ends.

3. In a typewriting machine, a cylinder having end journals and with spaced longitudinal peripheral ribs, a roller spaced from said cylinder and provided with end journals, arms connected respectively to the journals of the cylinder and roller and over-lapping at their free ends, means for adjustably coupling said over-lapping ends, tie members uniting the arms of said cylinder, tie members uniting the arms of said roller, and an endless belt extending over 60 said cylinder and roller.

4. In a typewriting machine, a carriage including end frames having oppositely disposed bearing slots at one end and spaced lateral pins at the other ends, a cylinder having end journals engaging said bearing slots and with spaced longitudinal peripheral ribs, arms engaging the journals of said cylinder, arms having transverse bearing slots and with spaced longitudinal slots movably engaging said spaced pins and over-lapping the free end of said cylinder arms, means for adjustably coupling the over-lapping ends of said several arms, a roller having journals engaging the bearing slots of said slotted arm, and an endless belt extending over said cylinder and said roller.

5. In a typewriting machine, a carriage including end frames having oppositely disposed bearing slots at one end and spaced lateral pins at the other ends, a cylinder having end journals engaging said bearing slots and with spaced longitudinal peripheral flanges, said flanges having vent apertures communicating with the spaces between the ribs, arms engaging the journals of said cylinder, arms having transverse bearing slots and with spaced longitudinal slots movably engaging said spaced pins and over-lapping the free ends of said cylinder arms, means for adjustably coupling the over-lapping ends of said several arms, a roller having journals engaging the bearing slots of said slotted arms, and an endless belt extending over the roller and cylinder.

JOSEPH H. JACKSON.
